UNITED STATES PATENT OFFICE.

JAMES C. KIMSEY, OF PHILADELPHIA, PENNSYLVANIA.

MACHINE FOR STRINGING TAGS.

SPECIFICATION forming part of Letters Patent No. 736,406, dated August 18, 1903.

Application filed December 11, 1901. Serial No. 85,513. (No model.)

To all whom it may concern:

Be it known that I, JAMES C. KIMSEY, a citizen of the United States, and a resident of Philadelphia, in the county of Philadelphia, 5 and State of Pennsylvania, have invented a Machine for Stringing Tags, &c., of which the following is a full, clear, and exact specification.

This invention relates to machines for attaching strings to tags, and is more especially an improvement upon the machine shown and described in my prior application for patent, filed December 4, 1901, Serial No. 84,635, the object of the present invention being to provide special mechanism for feeding the tags in a continuous strip to the stapling-machine and for severing a tag from the strip simultaneously with the attachment of the tag to the string or cord, also to provide improved 15 means for drawing the tags from the stapling-machine through the intervention of the continuous string or cord, for cutting said cord, and for depositing the finished tags in a box or jogger.

Having the above objects in view, the present invention consists in the particular construction and combination of parts, all as will be hereinafter fully described, and more specifically set forth in the appended claims.

In the accompanying drawings, which form a part of this specification, and in which like letters of reference indicate like parts in the several views, Figure 1 is a front elevation of a machine for stringing tags, &c., constructed in accordance with my invention. Fig. 2 is a top plan view of the machine. Fig. 3 is a transverse sectional view on the line 3-3 of Fig. 2. Fig. 4 is a detail sectional view on the line 4-4 of Fig. 2. Fig. 5 is a detail perspective view of the cutting-roll for notching the tag-strip. Fig. 6 is a detail view of the tag-strip. Fig. 7 is a detail sectional view of the pivoted cutting-blade which cuts the tags. Fig. 8 is a detail plan view of the stationary die of the stapling-machine.

Referring to said drawings, A designates the power-press of the stapling-machine, which is bolted to one side of a long table B, supported at its ends by the legs b, the top 50 of said table forming the bolster or bed-plate of the stapling-machine and also the support for the other mechanisms hereinafter de-

scribed. Said power-press comprises a vertically-reciprocating plunger A', working in a head-block and driven by an eccentric a on the main driven shaft a', the said plunger carrying at its lower end the staple-forming die a² and presser-bar a³, which coact with a stationary die a⁴, mounted on the top of the table B. The staple forming and clenching dies referred to are similar in construction to the like parts shown and described in my aforementioned application, with the exception that the stationary die or block a⁴ is cut away its entire width, as shown, so that the tag may pass through the stapling-machine from one side to the other instead of being passed under the block from the front thereof, as in the aforesaid application. This provision is made in order that a continuous tag-strip may be fed to the machine, as hereinafter particularly described.

Alongside the power-press is a reel c, loosely journaled on its bearing and carrying a metal strip c, from which the staples are formed, the said metal strip passing between the feeding-rolls c' c', suitably supported and driven by a belt which extends from a pulley on the shaft of the power-press. A spool D is mounted in bearings below the top of the table, and a cord d from said spool is guided to and through the block or stationary die a⁴ above the tag and in line to be engaged by the staple as it is attached to and clenched upon said tag, the said cord passing to the particular feeding and cutting mechanism therefor, hereinafter described. It will be noted that the aforesaid application for patent also includes the metal strip and string or cord by which the staple is made and the cord applied to the tag.

One of the features of my present invention is to provide for feeding a continuous strip to the stapling-machine and cut a tag from the strip simultaneously with the operation of applying the string and holding-staple, and to this end a continuous strip of paper or cardboard reinforced at one end is fed to the machine and first notched to give the usual shape to the end of the tag and then cut from the strip by a vibrating knife operated by the plunger which carries the staple forming and clenching dies. For this purpose a cutting-roll E is mounted on a shaft e, driven by a belt from a pulley on the driving-shaft of

the power-press, the said cutting-roll having on its periphery several sets of blades e' , each set comprising two blades disposed at an angle to each other, so as to cut a V-shaped notch f in the paper strip F . Alongside of the cutting-roll E is a feeding-roll g , fast to the shaft e , which, in conjunction with an idle-roll g' , located within the table-top, serves to feed the strip of paper or cardboard to the stapling-machine. The cutting knives or blades e' cut against a flat bed or pad e^2 , of hard rubber or cardboard. The strip F is reinforced by being doubled upon itself, so that the staple may have a better hold on the tag, said doubling of the strip being previously accomplished in any suitable manner.

Adjoining the stationary die of the stapling-machine is a pivoted cutting-blade H , which is adapted to cut the tags from the strip, the said blade having a spring h for returning it to its normal position and is carried by a bracket h' , slideable in a dovetailed recess in the top of the table, so that the said cutting device may be adjusted to cut tags of different widths. The stationary blade H' of this cutting device is also carried by the bracket, and its upper edge is flush with the top of the table, so that the tag-strip will pass freely over the same. The pivoted blade is provided with ears $h^2 h^2$, by which same is attached to the bracket. The speed of the feeding and cutting rolls is such with respect to the location of the knife-blade that the tags will be cut a certain width, and when the cutting device is adjusted the speed of the cutting-roll should be regulated accordingly. It is purposed to change the speed of the cutting-roll either by means of a graduated pulley or by substituting pulleys of different sizes. The V-shaped notch which is cut by the roll E not only gives the usual shape to the end of the tag, but said notch extends a sufficient distance beyond the metal strip so that the latter will not interfere with the operation of the cutting-blade H . Said cutting-blade is provided with an extension h^3 , which is struck by an arm b^5 , attached to and projecting laterally from the plunger A' of the power-press of the stapling-machine. This arm is adjusted on the plunger so that the knife-blade will sever a tag simultaneously with the clenching of a staple on the tag. Each tag as it is completed and strung is drawn from the stapling-machine by the continuous cord through the intervention of the cord-feeding device, which I shall now proceed to describe.

The tags pass from the stapling-machine along the top of the table to a pair of endless feeding-belts I and I' , by which they are carried to a box or jogger M , while the cord or string passes between a pair of friction-rolls $l l'$, the said friction-rolls serving to feed the cord or string through the stapling-machine and remove the finished tag which is attached to said cord or string. The speed of the friction-rolls is such that upon each full stroke of the plunger A' a certain length of cord

will be pulled through the stapling-machine before the next staple is applied, and in this way the tags are strung upon the cord or string at regular intervals, the cord being cut as it passes from the friction-rolls by means of the cord-cutting device, hereinafter described. The tags pass between the pair of endless feeding-belts I and I' and may be deposited therefrom directly into the box M or may be deposited into an ordinary jogger for stacking the tags. The upper part of the belt I' is flush with the top of the table, and the rollers $i i'$, over which this belt passes, are loosely journaled, the said lower belt being driven by the upper belt I' , while the latter is driven by a power-belt n , extending from a pulley on the shaft of the power-press. The roller i , over which the endless belt or apron I passes, is provided with a shaft i^2 to receive the pulley i^3 , over which the belt n passes, and to this pulley are attached tappets o , which operate a pivoted knife-blade adapted to cut the string or cord into proper lengths.

The cord-cutting device consists of a frame P , let into the top of the table and secured thereto, a stationary blade p , secured to said frame, and a pivoted blade p' , also carried by the frame, said pivoted blade having a rearward extension or arm p^2 , which is struck by the tappet. The pivoted cutting-blade is returned to its normal position by means of a spring p^3 . It will be noted, therefore, that the driven shaft i^2 not only serves to turn the endless feeding belts or aprons I and I' , but also serves to operate the knife which cuts the string.

The devices herein shown and described for feeding a continuous tag-strip to the stapling-machine and for feeding the string to said machine and removing the tags therefrom provide a complete tag-stringing machine which is simple in construction, regular and positive in its operation, and automatic. The machine can be run at a rapid rate of speed, and the strings will be securely and firmly attached to the tags.

From the foregoing description, in connection with the accompanying drawings, the operation of the improved devices which form the subject-matter of this application will be readily apparent, for the paper strip F , passing between the feed-rolls g and g' , is notched at its reinforced end by means of the cutting-roll E and passes over the top of the table into position under the stationary die of the stapling-machine, so that it may receive the staple by which the cord is attached thereto. The cord from the spool also passes under the stationary die, above and across the paper strip, and over the top of the table to the friction-rolls l and l' , by which said cord is pulled through the machine, while the metal strip C is fed into the stationary die, so that the staples can be stamped therefrom as the plunger descends. Upon each downward stroke of the plunger a staple is

forced into the tag and clenched, while the points are formed for another staple, and to this end the staple-forming die, in conjunction with the die-plate α^4 , cuts a staple from the metal strip and applies it to the tag. Simultaneously with the operation of clenching a staple the cutting-blade H cuts a tag from the tag-strip, and when said tag is released the cord pulls it from the stapling-machine, while the tag-strip is fed forward to place another tag in the stapling-machine. The friction-rolls l and l' feed the cord continuously, and as the operation of the plunger is very rapid the resiliency of the cord will take up the stop-motion or the cord may slip between the rolls. The tags pass from the stapling-machine to the endless belts or aprons I and I' and are carried thereby to the box or jogger, while the cord after passing between the friction-rolls is cut by the pivoted knife-blade operated by the tappet-wheel. It will be observed, therefore, that the several devices operate successively to feed the tag-strip to the stapling-machine, attach the cord to a tag and remove said tag from the strip, draw the tag from the stapling-machine through the intervention of the continuous cord or string, cut the cord between the strung tags, so that the tags will have strings of uniform length, and finally deposit the completed tags into a box or jogger.

In order to guide the scrap metal of the strip C from the machine, a curved plate or trough S is attached to the stationary die α^4 .

The advantages of attaching strings to tags by means of staples will be readily appreciated, as it not only permits the operation of stringing tags to be accomplished by machinery, but also attaches the string more securely, especially if a wide staple is used and the points properly clenched on the under side.

Having thus described my invention, what I claim as new, and desire to secure by Letters Patent, is—

1. In a tag-stringing machine, the combination, of a stapling-machine for attaching a staple and string to the tag, means for feeding a tag-strip to said stapling-machine, friction-rolls for drawing the string through the machine, a device for cutting the string after it passes through the friction-rolls, and means for separating the tags from the tag-strip, substantially as shown and described.

2. In a tag-stringing machine, the combination, of a stapling-machine for attaching a staple and string to the tag, means for feeding a tag-strip to said stapling-machine, and means for separating the tags from the strip; together with means for feeding a continuous string across the tag, friction-rolls between which the string passes from the stapling-machine, a pivoted knife for cutting the string, and means for operating said knife, substantially as shown and described. 55

3. In a tag-stringing machine, the combination, of a stapling-machine for attaching a staple and string to the tag, means for feeding a tag-strip to said stapling-machine, and means for separating the tags from the strip; together with means for feeding a continuous string across the tag, friction-rolls through which the string passes, a pivoted knife beyond the friction-rolls, and a tappet-wheel having tappets adapted to operate the knife, substantially as shown and described. 70 75

4. In a tag-stringing machine, the combination, of a stapling-machine for attaching a staple and string to the tag, means for feeding a tag-strip thereto, and means for separating the tags from the strip; together with means for feeding a continuous string or cord, friction-rolls between which the string or cord passes, means for cutting the string or cord, and endless belts or aprons between which the tags pass to a receptacle or jogger, substantially as shown and described. 80 85

5. In a tag-machine, the combination, of a stapling-machine for attaching a staple and string to the tag, means for feeding a tag-strip thereto, means for feeding a continuous cord or string through the stapling-machine, friction-rolls for drawing the cord through the stapling-machine, endless belts or aprons receiving and carrying the tags to a stacker, and means for cutting the cord or string as it passes from the friction-rolls; together with means for separating the tags from the tag-strip simultaneously with the attachment of a staple to the tag, substantially as shown and described. 90 95 100

In testimony whereof I affix my signature in the presence of two witnesses.

JAMES C. KIMSEY.
